Primary Examiner — Susan Moon Lee(74) *Attorney, Agent, or Firm* — Young & Thompson(57) **CLAIM**

I claim the ornamental design for an animal feeder, as shown and described.

DESCRIPTION

FIG. 1 is a front view of an animal feeder;
 FIG. 2 is a side view of an animal feeder;
 FIG. 3 is a back view of an animal feeder;
 FIG. 4 is a top view of an animal feeder;
 FIG. 5 is a bottom view of an animal feeder;
 FIG. 6 is a perspective view of an animal feeder; and,
 FIG. 7 is a perspective view of an animal feeder showing a teat
 mounted to the feeder in second position.
 Broken lines and portions contained within broken lines are
 not claimed.
